UNITED STATES PATENT OFFICE.

GEORGE A. AMBLER, OF WINCHESTER, MASSACHUSETTS, ASSIGNOR TO UNITED SHOE MACHINERY COMPANY, OF PATERSON, NEW JERSEY, A CORPORATION OF NEW JERSEY.

WIRE-FEEDING MECHANISM.

1,072,803.

Specification of Letters Patent.

Patented Sept. 9, 1913.

Original application filed October 26, 1906, Serial No. 340,707. Divided and this application filed October 12, 1911. Serial No. 654,236.

To all whom it may concern:

Be it known that I, GEORGE A. AMBLER, a citizen of the United States, residing at Winchester, in the county of Middlesex and 5 State of Massachusetts, have invented certain Improvements in Wire-Feeding Mechanisms, of which the following description, in connection with the accompanying drawings, is a specification, like reference characters 10 on the drawings indicating like parts in the several figures.

This invention relates to wire feeding mechanism and particularly to wire feeding mechanism which is especially adapted for 15 use in fastening inserting machines in which the fastening is formed from a measured length of wire.

One of the objects of the invention is to 20 provide a wire feeding mechanism which will feed into fastening forming position predetermined lengths of wire at whatever speed the machine may be operated.

In designing a fastening inserting machine to operate at high speed one of the 25 difficulties encountered has been that of providing a wire feeding mechanism which is so positive in its operation that the required length of wire will be fed for each operation of the machine, particularly when provision 30 is made for varying the length of the fastening by varying the amount of wire fed. In the machine to which the invention is herein shown as applied it is desired that a uniform length of wire be fed to the fastening forming mechanism for each of the successive operations of the machine upon a single piece of work, the machine being especially 35 adapted for performing the operation known as "slugging". Inasmuch as the slugs are 40 usually comparatively short, it is important that at least wire enough to form a slug of the full length be fed at each operation. It is, therefore, important that the operation of the wire feeding mechanism be positive.

Another object of the invention, therefore, 45 is the provision of a wire feeding mechanism which is so positive in its operation that when adjusted to feed a particular measured length of wire it will feed this 50 length with precision at each operation.

A further object of the invention is to provide a wire feeding mechanism which may be easily thrown out of operation when it is desired to interrupt the feeding of wire.

Other objects of the invention will be apparent from a consideration of the following description and claims in connection with the accompanying drawings, in which,—

Figure 1 is a side elevation of the upper 55 part of a machine for inserting fastenings having embodied therein a preferred form of the wire feeding mechanism of this invention; Fig. 2 is a front elevation drawn to a slightly larger scale; Fig. 3 is a detail front 60 elevation partly in section of the essential parts of the wire feeding mechanism, and Fig. 4 is a detail side elevation, also partly 65 in section, of the wire feeding mechanism.

The machine in which the invention is 70 shown as embodied is adapted especially for performing the operation known as "slugging" and is more fully shown and described in my Patent No. 1,005,920, granted October 17, 1911, of which patent the present 75 application is a division. For the purposes of this application it will suffice to point out the principal parts of the said machine with which the wire feeding mechanism is associated or from which it is operated. 80

The machine comprises a standard 12 upon which is mounted the head 14. A driving shaft 16 is carried in suitable bearings in the head 14 and is driven from any suitable source of power by means of a belt 85 passing over the fixed pulley 18, the belt being transferred to the loose pulley 20 when it is desired to stop the driving shaft. Normally the driving shaft is kept in motion and the insertion of fastenings is stopped by 90 stopping the wire feed and by throwing the awl out of operation, as more fully set forth in the patent above identified. A hand wheel 22 is provided for turning the shaft over slowly by hand when the power is disconnected. At the forward end of the shaft 16 is a cam disk 24 having formed in it a cam groove 26 from which the driver is operated, this cam groove also serving to transmit movement to the wire feeding 95 mechanism in proper time relation to the movement of the driver. A second cam disk 58 is provided with a cam groove from which the awl is operated.

The wire feeding mechanism herein illustrated 100 comprises an arm 92 mounted loosely upon a rock-shaft 90, the arm 92 being loosely connected by a link 94 to a lever 96,

pivoted at 97 upon the frame 14 and given
 an oscillatory motion by means of a roll
 connection 98 with the cam groove 26 hereinabove
 referred to. It is seen that with
 5 such connection the arm 92 is moved posi-
 tively in two directions through a deter-
 mined distance. For varying this distance
 the link 94 is adjustably connected to the
 10 lever 96 through a pin and slot connection
 100 and by the adjustment of this connection
 the movement of the arm 92 may be length-
 ened or shortened. The arm 92 carries a
 15 wire gripper in the form of a pawl 102 pivoted
 on the arm at 104 and provided with
 a serrated edge eccentric with its pivot, as
 is usual. A spring 106 controls the move-
 20 ment of the gripper in one direction and
 a stop 108 limits its action under the force
 of the spring. The wire W is led from a
 25 suitable source of supply through a guide
 110 to be hereinafter described and past the
 serrated edge of the wire gripper 102 into
 a guide or groove 112 in the machine and
 thence to the wire severing mechanism. The
 30 arm 92 also carries on the side of the wire op-
 posite to the gripper 102 a movable presser
 114, having preferably a rounded surface
 which is normally inoperative to aid in
 gripping the wire. A preferred form of
 35 mechanism for rendering this mechanism
 114 operative comprises a U-shaped arm 116,
 which may be termed a wire feeding controller,
 having its legs securely mounted on the
 rock-shaft 90, one on each side of the wire
 40 feeding arm 92. The rock-shaft 90 is rocked
 by suitable connections with the awl oper-
 ating cam 58 hereinabove referred to. These
 connections may comprise, as herein shown,
 an arm 89 fixed on the rock-shaft 90 and
 45 connected by an adjustable connection 88
 with a second arm 47 upon a rock-shaft 48,
 which is constantly rocked while the main
 shaft is in operation by connections with
 the cam 58 comprising a lever arm 52 hav-
 50 ing at its upper end a cam roll which enters
 a groove in the cam 58. The adjustable con-
 nection 88 is set when the machine is first
 set up so that the throw of the cam 58 will
 impart to the wire feeding controller 116
 55 a movement sufficient to feed the longest
 fastening desired. The adjustment of the
 connection 88 is not thereafter altered. The
 U portion of the arm 116 is provided on
 its inner side with a spring-pressed plug
 60 118 having a surface consisting of a beveled
 portion 120 and a face 122 which is eccen-
 tric to the pivotal center of the arm 92. As
 the feed controller moves upwardly, the sur-
 face 120 of plunger 118 engages the presser
 65 114, forcing it toward the wire and thus
 forming an unyielding surface against which
 the wire may be gripped by the gripper 102
 as the arm 92 moves downwardly, the feed
 controller at this time also moving down-
 70 wardly with the arm and maintaining its

pressure on the wire. The feed controller is
 also provided with a screw 124 having an
 eccentric head 126 adapted to bear against a
 portion of the plug 118 for varying the position
 of the plug to accommodate the feed of 70
 wire of varying sizes.

The cams 24 and 58 controlling respec-
 tively the movements of the arm 92 and the
 wire feed controller 116 are so designed and
 mounted on the main shaft that the arm 92 75
 returns to its starting position while the
 feed controller 116 is held stationary at the
 lower end of its stroke, whereby the presser
 80 114 is again released and the gripper 102
 thereby rendered inoperative to feed the
 wire. On its way through the guiding
 groove 112 the wire passes a spring-pressed
 pawl 128 arranged to prevent backward
 movement of the wire during the time the
 85 arm 92 is returning to its initial position
 preparatory to making another feeding
 stroke. This pawl 128 may be rendered
 inoperative when desired through an eccen-
 tric 130 on one end of a hand lever 131.
 After passing pawl 128 the wire is forced 90
 by the movement of the feeding arm 92 into
 a hole 132 in a sliding block 134. The hole
 132 registers with the hole 112 when the
 block 134 is at one of the limits of its slid-
 95 ing movement. A reciprocation of this
 block 134 acts to shear off the length of wire
 which has been fed into the hole 132 and to
 bring the severed portion in line with the
 driver 32.

If the machine is to drive two fastenings 100
 at each operation provision must be made
 for feeding two lengths of wire and this is
 preferably done as herein shown by dupli-
 cating the wire feeding mechanism so that
 105 a length of wire is fed from each of two
 strips. As shown in the drawings, a second
 feeding arm 92' is provided which carries
 feeding devices similar to those of the arm
 92 heretofore described. This arm 92' may
 be connected by a link 94', through an ad-
 justing mechanism similar to 100, to the
 110 lever 96. The feed controller 116 is
 made large enough to embrace both of the
 wire feeding arms and is provided with a
 second spring plug 118' and adjusting cam
 115 126' to coöperate with the devices of arm 92'.

Loosely mounted on the shaft 90 is an arm
 190 provided with a hook-shaped end 192
 which has two surfaces 194 and 196 concen-
 tric with the axis of the shaft 90 but of un-
 equal radii. The arm 190 may be oscillated
 120 through an extension 191 to give movement
 to the end 192. When arm 190 is in the po-
 sition shown in dotted lines in Fig. 3, the
 surface 196 engages the pin 198 which pro-
 jects from the gripping pawl 102' and serves
 to confine one end of the spring which acts
 upon said pawl. If the end 191 of the arm
 190 is moved to the left, Fig. 3, the surface
 125 194 will be placed in engagement with the
 130

pin 198 and the gripping pawl 102' will be forced downwardly against the action of its spring to a position where it cannot engage the wire W' being led past it. The machine 5 is by this means converted into a single row machine. As herein shown, the movement of the arm 190 is placed under the control of the operator through a lever 200 and a rock-shaft 202 connected in any suitable manner 10 with a knee lever or other manually controlled means.

The wire guide 110 may be of any suitable construction. Inasmuch as the wire guide does not form a feature of the invention 15 herein claimed, it is sufficient for the purposes of this specification to point out that it is provided with two anti-friction members, such as rolls 204 and 206, the distance between which may be adjusted by means 20 of a set screw 208 so that any thickness of wire may be admitted between them. In order to insert or remove the wire from the guide, one of the rolls may be yieldingly mounted and connected to a hand operated 25 eccentric 210 which may be rotated to withdraw it from the other roller. These rollers may be so formed and positioned as to present correctly any character of wire to the feeding devices. In the use of the invention 30 the arm 92, carrying the spring-pressed pawl 102 and the presser 114, between which the wire W is held, comes to rest in position to determine the feed of a definite length of wire at the next operation of the machine. 35 When the machine is started the wire controller 116 moves upwardly about pivot 90 a distance sufficient to cover the longest movement of the arm 92 and the beveled surface 120 of the yieldingly supported lug 40 118 on the controller 116 contacts with the wire presser 114, causing the wire to be gripped between the pawl 102 and the presser 114, any excess of movement of the controller 116 after it has acted on the 45 presser being taken up by the yieldingly supported plug 118. The arm 92 is now moved downwardly to feed the length of wire to the severing mechanism, the feed controller 116 also moving downwardly with 50 the arm 92 and maintaining its pressure on the wire through the presser 114. The cams are so timed that the arm 92 returns in advance of the controller 116, thereby releasing the grip of the presser 114 on the wire 55 and stops in such position that it will feed the required length of wire on the succeeding operation of the machine.

Having described my invention, what I claim as new and desire to secure by Letters 60 Patent of the United States is:—

1. In a machine of the class described, a reciprocating feeding arm carrying a wire gripper and a normally inoperative wire

presser arranged to act upon the opposite side of the wire, and means arranged to 65 travel with said arm and movable relatively thereto for engaging said presser at the top of the stroke of the feeding arm to render the gripper operative to feed wire and means for positively effecting the relative movement of said arm and said engaging means.

2. In a machine of the class described, a pivoted arm, means for oscillating said arm about its pivot, a wire gripper and a normally inoperative wire presser carried by said arm, a second arm mounted on said pivot having a surface eccentric therewith, and means for oscillating said second arm to bring said eccentric surface into engagement with said presser at the top of the stroke of the first-named arm to render the gripper operative to feed wire.

3. In a machine of the class described, a plurality of reciprocating arms each provided with a wire-gripping pawl for feeding wire and arranged to be operated simultaneously with another arm to feed the wire, and movable means constantly engaging one of said pawls constructed to lock 90 said pawl out of action when in one position and to allow it to freely perform its function when in another position whereby the number of wires fed at a single operation may be varied.

4. In a machine of the class described, a plurality of reciprocating arms each provided with a wire gripping pawl for feeding wire and arranged to be operated simultaneously with another arm to feed the wire, 100 and movable means under control of the operator constantly engaging one of said pawls and constructed to lock said pawl out of action when in one position and to allow it to freely perform its function when 105 in another position whereby the number of wires fed at a single operation may be varied.

5. In a machine of the class described, a plurality of pivoted arms each provided 110 with a wire gripping pawl for feeding wire, means for oscillating said arms, a movable member mounted on said pivot adjacent to one of said arms constantly engaging one of said pawls with one of two surfaces thereon 115 each concentric to said pivot but of different radii, whereby said pawl may be rendered operative or inoperative to feed wire.

In testimony whereof I have signed my name to this specification in the presence of 120 two subscribing witnesses.

GEORGE A. AMBLER.
